US0D1055978S

(12) **United States Design Patent** (10) **Patent No.:** **US D1,055,978 S**
(45) **Date of Patent:** **** Dec. 31, 2024**

(54) **PERISTALTIC PUMP**

(71) Applicants: **DEKA Products Limited Partnership**, Manchester, NH (US); **CAREFUSION 303, INC.**, San Diego, CA (US)

(72) Inventors: **Larry B. Gray**, Merrimack, NH (US); **Thomas A. Friedrich**, Loudon, NH (US); **Craig A. Dodge**, Tyngsborough, MA (US); **Christopher J. Murray**, Philadelphia, PA (US); **Edward G. Mitchell**, Philadelphia, PA (US); **Gregory T. Hulan**, Poway, CA (US); **Philip T. Pupa**, San Diego, CA (US)

(73) Assignees: **DEKA Products Limited Partnership**, Manchester, NH (US); **CAREFUSION 303, INC.**, San Diego, CA (US)

(**) Term: **15 Years**

(21) Appl. No.: **29/771,289**

(22) Filed: **Feb. 22, 2021**

(57) **CLAIM**

The ornamental design for a peristaltic pump as shown and described.

DESCRIPTION

FIG. 1 is a front, top, and left-side perspective view of the peristaltic pump, showing our new design;

FIG. 2 is a front, top, and left-side perspective view thereof, with a hinged piece retracted;

FIG. 3 is a front, bottom, and left-side perspective view thereof;

FIG. 4 is a left-side elevational view thereof;

FIG. 5 is a right-side elevational view thereof;

FIG. 6 is a bottom plan thereof;

FIG. 7 is a top plan view thereof;

FIG. 8 is a front elevational view thereof;

FIG. 9 is a back elevational view thereof;

FIG. 10 is a front, top, and left-side perspective view of another embodiment of a peristaltic pump, showing our new design;

FIG. 11 is a front, top, and left-side perspective view thereof, with a hinged piece retracted;

FIG. 12 is a front, bottom, and left-side perspective view thereof;

FIG. 13 is a left-side elevational view thereof;

FIG. 14 is a right-side elevational view thereof;

FIG. 15 is a bottom plan thereof;

FIG. 16 is a top plan view thereof;

(Continued)

FIG. 17 is a front elevational view thereof; and, FIG. 18 is a back elevational view thereof. The ornamental design which is claimed is shown in solid lines in the drawings. The broken lines depict portions of the peristaltic pump that form no part of the claimed design.

1 Claim, 16 Drawing Sheets
